Primary Examiner — Llorellys Martinez-Rivera*(74) Attorney, Agent, or Firm* — Andrew F. Young; Nolte Lackenbach Siegel(57) **CLAIM**

The ornamental design for a jewelry article as shown and described.

DESCRIPTION

FIG. 1 is a front right perspective view of a jewelry article of my present invention.

FIG. 2 is a right side elevation view thereof.

FIG. 3 is a left side elevation view thereof.

FIG. 4 is a front elevation view thereof.

FIG. 5 is a rear elevation view thereof.

FIG. 6 is a top plan view thereof; and,

FIG. 7 is a bottom plan view thereof.

The broken lines in the drawings represent portions of the jewelry article and form no part of the claimed design.
